Primary Examiner — Kelley Donnelly(74) *Attorney, Agent, or Firm* — Gardner, Linn, Burkhardt & Flory, LLP(57) **CLAIM**

The ornamental design for the carpet display, as shown and described.

DESCRIPTION

FIG. 1 is a front perspective view of the carpet display of the present invention, shown mounted at a display assembly; FIG. 2 is a front perspective view of the carpet display of FIG. 1, shown mounted at a display frame of the display assembly; FIG. 3 is a left side elevation of the carpet display and display frame of FIG. 2; FIG. 4 is a front elevation of the carpet display of FIG. 1; FIG. 5 is rear elevation of the carpet display of FIG. 1; FIG. 6 is a right side elevation of the carpet display of FIG. 1; FIG. 7 is a left side elevation of the carpet display of FIG. 1; FIG. 8 is a top plan view of the carpet display of FIG. 1; FIG. 9 is a bottom plan view of the carpet display of FIG. 1; and,

FIG. 10 is another perspective view of the carpet display, shown with a carpet sample mounted thereon. The broken lines are included for the purpose of illustrating portions of the carpet display that form no part of the claimed design.
